UNITED STATES PATENT OFFICE.

HARRY RUBIN, OF NEW YORK, N. Y.

DESIGN FOR AN INVERTED GAS ARC-LAMP.

43,347.

Specification for Design.

Patented Dec. 17, 1912.

Application filed September 27, 1912. Serial No. 722,764. Term of patent 3½ years.

To all whom it may concern:

Be it known that I, HARRY RUBIN, a citizen of the United States, residing in the borough of Bronx, city of New York, county and State of New York, have invented a new, original, and ornamental Design for an Inverted Gas Arc-Lamp, of which the following is a specification, reference being had to the accompanying drawings, forming part thereof.

The drawing is a side elevation of an inverted gas arc lamp, showing my new design.

I claim:

The ornamental design for an inverted gas arc lamp, as shown.

In testimony whereof, I have hereunto set my hand in the presence of the two subscribing witnesses.

HARRY RUBIN.

Witnesses:

WILLIS FOWLER,
HARRY I. PICKETT.
